UNITED STATES PATENT OFFICE.

JOSEPH D. VIRDIN, OF BALTIMORE COUNTY, MARYLAND.

FORT.

1,263,969.

Specification of Letters Patent. Patented Apr. 23, 1918.

Application filed October 23, 1916. Serial No. 127,136.

To all whom it may concern:

Be it known that I, JOSEPH D. VIRDIN, a citizen of the United States, residing in Baltimore county, State of Maryland, have 5 invented a new and useful Improvement in Forts, of which the following is a specification.

My invention relates to improvements in 10 forts or fortifications for use in coast or other defenses.

The primary object of this invention is 15 the construction of a permanently located submerged fort wherein the entire housing or fort, its occupants and armament are concealed from view and protected, the entire fortification being surrounded and completely covered by water.

A further object is the construction of a 20 fort of this character provided with means, such as periscopes or the like, whereby the location of the enemy or others may readily be ascertained from within the fort and without exposing the occupants or the fort itself to danger.

25 A further object is the provision in a fort of this character wherein the entire fort is submerged, with means of access leading under the surrounding water to a base or other location in order that supplies of any 30 kind may be conducted back and forth to the fort without exposure.

In the accompanying drawings I have 35 shown one form of structure embodying my invention, although it is to be understood that I do not desire to be limited to the exact details or structure therein shown.

In said drawings:

Figure 1 illustrates in vertical section a 40 fort built in accordance with my invention, and

Fig. 2 is a plan view of the same.

Referring to the drawings wherein similar letters of reference are used to indicate corresponding parts in each of the several views, 1 indicates the top or roof of the fort, which as herein shown is circular in form, provided with wall 2. The wall and roof may be constructed, and preferably are constructed of some rust-proof material, not 45 affected by water, although it may be equally well constructed of masonry or any other desired material.

Suitably mounted in the fort in position to be handled by the necessary operators are 50 any desired number of mortars 3, being so arranged, constructed and mounted on the

elevating base 4 as to be capable of being raised and lowered through openings 5, above and below the surface of the water covering the fort when it is desired to operate or discharge said mortars. The openings 5 are provided with the proper gates or slides 6 so as to prevent the entrance of water into the fort through said opening.

I also provide one or more periscopes 65 which are so arranged and located as to reveal to the occupants of the fort the position of the enemy or points upon which attack is to be made.

Leading from the fort proper are a series 70 of tunnels or passages 8 which extend beneath the water and through the land surrounding said water whereby all necessary supplies may be taken in and out of the fort and a means provided for ingress and 75 egress of the occupants of the fort, without in any way exposing such occupants or supplies to the enemy or outside parties.

The normal position of the mortars 3 is such that the muzzle 9 thereof is above the 80 surface of the water and is the only part of the armament exposed to view. While these mortars are normally in this position it is to be understood that if desired the same may be raised or lowered at the will of 85 the operators.

It may be desirable in a fort of this character to have large guns or rifles arranged at such an elevation as to be above the surface of the water, and in such cases I provide a revolving casing 10 which may or may not be submerged as desired, but in the instance shown extends upwardly from the roof or top of one of the tunnels and is provided with a covering of armor plate 11, 95 which extends below the surface of the water any desired depth for protecting the structure of the casing, and through which is projected the muzzle or barrel of the gun or rifle 12. In this instance the muzzle or 100 barrel is the only portion of the rifle or gun exposed to attack or danger and the operators or vital parts of the gun are protected by the armor plate 11. This casing 10 might equally as well be projected upwardly from 105 the main roof 1 of the fort.

As stated the entire housing forming the fort or fortification not only is covered and surrounded by a body of water as 12 but surrounding said body of water 12 is a body 110 of land as 13.

While I have described the fort or fortifi-

cation as being constructed or applied on the coast it will be apparent and obvious that the same could with equal facility and adaptability be built in a body of water or stream proper in which case the body of land 13, for instance, would have to be built up and around the body of water 12, thereby protecting the fort or fortification from attack by submarines or torpedoes, the body of land 13 acting as a protection against such underwater attack.

If desired one or more torpedo tubes as 14 may be provided, said tubes extending through the surrounding body of land 13 and the outer ends of the tubes being provided with the necessary and usual torpedo gates or closures 15. By the use of these torpedo tubes the torpedoes may be discharged from the fort into the main body of water or stream on the outside of the body of land 13.

It will be obvious that in time of peace or otherwise when it is not necessary to have the fort concealed, the water surrounding and covering the fort may be removed and any suitable means may be provided, such as sluice gates or the like whereby the water may be admitted or removed as desired.

Having thus fully described my invention what I claim as new and desire to secure by Letters Patent of the United States is:

1. A fort of the character described com-

prising a housing for the operators of the armament thereof, armament suitably mounted therein, in combination with a body of water encircling and covering said housing and a body of land encircling said body of water, and means for preventing the entrance of water into said housing during the operation of said armament, substantially as and for the purpose set forth. 40

2. A fort of the character described comprising a housing for the operators of the armament thereof, armament suitably mounted therein, in combination with a body of water encircling and covering said 45 housing, a body of land encircling said body of water, means for preventing the entrance of water into said housing during the operation of said armament, and torpedo tubes extending through said body of land, substantially as and for the purpose set forth.

3. A fort of the character described comprising a housing for the operators of the armament thereof, armament suitably mounted therein, in combination with a body 55 of water encircling and covering said housing, a body of land encircling said body of water and passages or tunnels leading from said fort to a base of supplies and the like substantially as and for the purpose set forth.

JOSEPH D. VIRDIN.
